SEWING MECHANISM

Samuel W. Avis, Providence, R. I., assignor to The
Reece Button Hole Machine Company, Boston,
Mass., a corporation of Maine

Application October 14, 1938, Serial No. 235,012

11 Claims. (Cl. 112—159)

This invention relates to sewing machines and more particularly to novel mechanism in a sewing machine for coordinating the thread handling element thereof with a reciprocating and laterally moving needle for constant cooperation.

It is the primary aim and object of the present invention to provide novel mechanism for constantly coordinating a laterally immovable, rotating thread-handling element with a reciprocating and laterally vibrating needle such that the loop-seizing portion of said element seizes each loop which is cast by the needle on slight recession from either of its different lowermost positions.

It is another object of the present invention to provide for adjustment of the novel mechanism so that the thread-handling element will seize each cast loop in spite of selective variation of the amplitude of the needle vibration.

It is another object of the present invention to make provisions in the mechanism for additional constant coordination of the thread-handling element with the needle in accord with a second lateral movement of said needle transversely to the plane of oscillation of the latter so that the thread-handling element will seize each loop on being cast by the needle in any of its various positions of operation.

It is another object of the present invention to provide for another adjustment of the mechanism so that the thread-handling element will seize each cast loop in spite of selective variation of the extent of said second lateral movement of the needle.

It is also among the objects of the present invention to provide a drive for operating either a bobbin case retainer for use with a shuttle, or a loop deflector for use with a looper.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawings:

Fig. 1 is a longitudinal section through a sewing machine which embodies the present invention.

Fig. 2 is a front elevation, partly in section, of the machine shown in Fig. 1.

Fig. 3 illustrates one example of the type of sewing accomplished with the present machine.

Fig. 4 is a fragmentary section taken substantially on the line 4—4 of Fig. 1.

Fig. 4a is a diagrammatic illustration of a modification of part of the operating structure shown in Fig. 4.

Fig. 5 is a fragmentary section taken substantially on the line 5—5 of Fig. 1.

Fig. 6 is a fragmentary perspective view of the operating structure disclosed in Figs. 4 and 5.

Figs. 7 to 10, inclusive, diagrammatically illustrate progressive steps in one cycle of operation of a needle, a rotary shuttle and a bobbin retainer, for the formation of a lock stitch.

Fig. 11 is a plan view of a shuttle.

Fig. 12 is an enlarged, fragmentary longitudinal section through a part of the machine disclosed in Fig. 1, showing, however, a rotary looper instead of a rotary shuttle.

Fig. 13 is a front elevation of the structure disclosed in Fig. 12.

Fig. 14 is a fragmentary section taken substantially along the line 14—14 of Fig. 12.

Fig. 15 is a perspective view of a rotary looper.

Figs. 16 to 21, inclusive, diagrammatically illustrate progressive steps in one cycle of operation of a needle, a rotary looper and a loop deflector, for the formation of a chain stitch.

Referring to the drawings and more particularly to Fig. 1, the present machine comprises a main frame 30 on which are suitably mounted a head 31 and a work table 32. A needle bar 35 is axially slidable in a sleeve 34 which is mounted in the head 31 for rotation about the axes of the transverse pivots 36 and 37, and serves as a fulcrum for said needle bar for oscillation in any direction. The needle bar 35 carries a needle 49.

Mounted in bearings 40 and 41 in the head 31 is a needle crank shaft 42 which carries a pulley 43 and a gear 44 at one end, and a balanced crank 45 at the other end. The shaft 42 may be driven from any suitable prime mover (not shown) by means of a belt 43a which is guided over the pulley 43. The crank 45 has any suitable driving connection 46, 47 and 48 with the needle bar 35 of such construction that the latter is reciprocated on rotation of the crank shaft 42, without interfering with any oscillatory movements of said needle bar.

Rotatably mounted in suitable bearings, provided by the head 31 and a lug 50 of a bracket 51 in the machine frame 30, respectively, is a

vertical shaft 52 on which is mounted a disk 53, having cam grooves 54, 55 and 56 in its opposite faces (Figs. 1, 4 and 5). The crank shaft 42 is provided with a worm 57 which is in permanent mesh with a worm gear 58 on the cam shaft 52 for driving the latter.

Pivotedly mounted at 60 in the machine frame 30 is a block 61, having a groove 62 in which a longitudinally movable bar 63 is guided. Secured to one end of this bar 63, hereafter called the "needle-oscillating bar" is a sleeve 64 in which the needle bar 35 is axially slidable. The sleeve 64 is rotatable about the axes of transverse pivots 65 and 66. Hence, the needle bar may be oscillated in any direction about its fulcrum 34 upon longitudinal movement of the needle oscillating bar 63 and/or rocking movement of the same about the pivot axis of the guide block 61. The other end of the bar 63 is provided with a longitudinally disposed guideway 25 (see particularly Figs. 4 and 6), which receives one end of a stud 67, carried by a link 68. The other, rectangular end 67a of the stud 67 (see particularly Fig. 1) is received in a guideway 26, provided in a head 27 which has its shank 28 pivoted in a bracket 29 in the head 31. The guideway 26 permits lateral movement of the stud 67 substantially in the direction of the arrow 26a (Fig. 4) and, consequently, oscillation of the bar 63, while holding said stud 67 practically immovable in the direction 26b (Fig. 4). The guideway 25, therefore, permits longitudinal movement of the needle-oscillating bar 63 relative to the stud 67 as hereinafter more fully explained. The other end of the link 68 carries a bolt 69, having its T-head 69a slidably received in an arcuate groove 70 of a lever 71 (Figs. 2 and 4). A nut 69b cooperates with the bolt 69 to lock the link 68 to the lever 71 in any desired position of said bolt within the confines of the arcuate groove 70. Lever 71 is rotatably mounted on a pivot 72 which is carried by a boss 73 of the head 31 (Fig. 1). The lever 71 has an arm 74 which carries a follower 75, cooperating with the cam groove 54 in the disk 53 (Fig. 4). The arcuate groove 70 in lever 71 is disposed concentrically of the pivot 67 when the needle oscillating bar 63 and the cam disk 53 assume the home or rest position illustrated in Fig. 4. It is then possible to rock the link 68 about the pivot 67 so that the bolt 69 may assume any desired position within the arcuate groove 70, without rocking bar 63 about its pivot 60. Clockwise rotation of the cam disk 53 as viewed in Fig. 4 will cause oscillation of the bar 63 about the pivot 60 of the guide block 61 through intermediation of cam groove 54, lever 71 and link 68, thereby imparting oscillatory movements to the needle bar 35 in a plane at right angles to the longitudinal axis of said bar 63. By adjusting link 68 such that the bolt 69 is in coaxial alinement with the pivot 72, no oscillatory movements are imparted to the bar 63 in spite of oscillation of the lever 71.

Rotatably mounted in a tubular extension 76 of the bracket 51 (Figs. 1, 5 and 6) is a vertical shaft 77 on the upper end of which are mounted two levers 78 and 79 (Fig. 4). Lever 78 carries a follower 81 which cooperates with the cam groove 55, and lever 79 is connected at 82 with a link 83. Link 83 is also pivotally connected at 84 with an arm 85, with the pivot 84 extending into a transverse groove 86 in the needle oscillating bar 63. Arm 85 is rotatably mounted at 80 on a side wall of the head 31. On rotation of the cam disk 53 in clockwise direction as viewed

in Fig. 4, the needle oscillating bar 63 is moved longitudinally through intermediation of cam groove 55, levers 78 and 79, link 83, pivot 84 and arm 85. Due to the substantially spiral design 5 of the cam groove 55 as shown in Fig. 4, a comparatively slow longitudinal motion in one direction is imparted to the bar 63, followed by a 10 rather sudden return motion of said bar as caused by the "return" groove portion 55a and a spring 10 87 which constantly urges the lever 78 inwardly toward the cam shaft 52.

It can now be understood that on rotation of the cam disk 53, the needle bar 35 is oscillated in two planes which are transverse to each other, 15 and that the drives therefor are separate units which operate independently of each other.

Referring now to Figs. 1, 5 and 6, the horn 94 of the machine, formed by a forwardly extending part of the machine frame 30 and the work table 32, has mounted therein a bracket 95 which supports the cam block 96 of a combined support and drive 97 for either a rotary shuttle or a rotary looper. This combined support and drive 97 is disclosed in, and forms the subject 20 matter of, my copending application Serial No. 185,538, filed January 18, 1938.

More particularly, the cam block 96 is non-rotatable, but axially slidable, in the bracket 95 and has a continuous cam surface 98 with which 30 cooperates a plurality of angularly spaced pawls 99, pivoted at 100 on a carrier sleeve 101 which is rotatably mounted in said cam block 96. An annular shoulder of the carrier sleeve 101 is retained in permanent engagement with a similar 35 shoulder of the cam block 96 as indicated at 102 by means of a collar 104 which abuts said cam block, thus preventing axial movement of the carrier sleeve 101 relative to the cam block 96. The pawls 99 have depending fingers 5 and 40 are so operated by the cam surface 98 that these fingers enter correspondingly formed apertures 6 in the periphery of a rotary shuttle or a rotary looper to support the same at all times, yet permit either the passage of a non-twisted 45 loop of needle thread completely around the shuttle, or the complete passage of the looper through said loop, all as described in my above-mentioned, copending application.

The carrier sleeve 101 is mounted on one end 50 of a shaft 110 which has its other end journalled in a bearing 111, provided by the bracket 51 (Fig. 1). Mounted in any suitable manner on the shaft 110 are two spaced collars 112 (Figs. 5 and 6), forming an annular groove 113 into 55 which projects a roller 114 of a shifter fork 115 which is mounted on the shaft 111 for rotation therewith. Hence, on rotation of the cam disk 53 in clockwise direction as viewed in Fig. 4, the cam groove 55 effects also axial movement of the 60 shaft 110 and of the combined support and drive 97 which is carried thereby.

The shaft 110 is driven in the following manner. Splined at 120 on the shaft 110 is a gear 121 of a comparatively wide periphery which is 65 in constant mesh with another gear 122, splined at 123 on an axially immovable counter shaft 124 which is mounted in bearings 125 and 126, provided by a bracket 127 in the horn 94 of the 70 machine and other suitable structure carried by the machine frame 30, respectively. One end of the counter shaft 124 carries a gear 128 which is in permanent driving relation with the gear 44 on the needle crank shaft 42 (Fig. 1) through intermediation of a suitably journalled idler gear 129. In order to prevent axial movement of the

gear 121 together with the shaft 110, a member 130 which is secured to the bracket 127 retains said gear in permanent abutment with said bracket.

Gear 122 has a sleeve-like portion 135 which is provided with an annular groove 136 wherein projects a stud 137, carried by one arm 138 of a bell crank lever 139 which is pivotally mounted at 140 on the bracket 127 (Fig. 1). The other arm 141 of the lever 139 is pivotally connected at 142 with a link 143 which carries a bolt 144 (Figs. 2 and 5), the T-head of which is slidably received in an arcuate groove 145 in a lever 146 which is carried by one end of a shaft 147, rotatably mounted in a boss 148 of the bracket 51 (Figs. 2 and 5). A nut 144b cooperates with the bolt 144 to lock the link 143 to the lever 146 in any desired position of said bolt within the confines of the arcuate groove 145. Mounted on the other end of the shaft 147 is an arm 149, carrying a follower 150 which is in permanent cooperation with the cam groove 56 in the lower face of the disk 53. This cam groove 56 (Fig. 5) is of such shape that, on rotation of the disk 53, the gear 122 is reciprocated on the counter shaft 124 through intermediation of levers 149 and 146, link 143 and lever 139. The gears 121 and 122 are spiral gears so that reciprocation of the gear 122 on the counter shaft 124 will cause slight rotations of the gear 121 in opposite directions by reason of the spiral mesh of the teeth of these gears. Hence, even though gear 122 is driven at uniform angular speed, it follows that the gear 121 has two alternating speeds, one being lower and the other higher than the uniform rotary speed of the gear 122, depending on the momentary direction of axial movement of the latter. The reason for rotating gear 121 at different rotary speeds will be explained hereafter.

The arcuate groove 145 in the lever 146 is disposed concentrically of the pivot 142 when said lever is in the home position shown in Fig. 5. Hence, when the machine is at rest, link 143 may be rocked about its pivot 142 and the bolt 144 may be adjusted in any desired position within the arcuate groove 145 without rocking the lever 139 and shifting the gear 122 from its home position. By adjusting the bolt 144 in the groove 145, the stroke of the reciprocating gear 122 and, hence, the two alternating speeds of the gear 121, may be varied as desired. In adjusting the link 143 such that the bolt 144 is in coaxial alinement with the pivot 142 of the lever 146, the rocking motion of the latter is not transmitted to the lever 139, with the result that gear 122 is not reciprocated and gear 121 will be driven at uniform speed.

Referring now more particularly to Figs. 7 to 10, inclusive, there is shown a shuttle 155 in various positions of cooperation with the vibrating needle 49. In order that the loop-seizing beak 160 of the rotary shuttle 155 may seize each loop of upper thread right after the same is cast by the needle 49 on slight recession from its alternately changing lowermost positions 49' and 49'' (Figs. 7 and 10), it is evident that the rotary speed of the shuttle 155 has to alternate between relatively slow and relatively fast. This is accomplished by the spiral gears 121 and 122, the latter of which is reciprocated.

The cam disk 53 is so driven from the needle crank shaft 42, and the cam grooves 54 and 56 are so coordinated, that the gear 122 is reciprocated once during two consecutive reciprocations of the needle 49 and during each lateral vibration

of the same in a plane at right angles to the needle crank shaft 42. However, since the shuttle 155 has to make approximately two revolutions to each reciprocation of the needle so that the take-up device 158 (Fig. 1) may have sufficient time to perform its operation between the casting of consecutive loops by the needle, the speed ratio between the gears 44 and 128 (Fig. 1) is 1 to 2. Hence, the shuttle 155 makes approximately two revolutions to each single stroke of the gear 122, with the result that the two rotary speeds of said shuttle alternate after approximately each second revolution thereof.

In Fig. 7, the needle 49 is sufficiently withdrawn from its one lowermost position 49', shown in broken lines, to cast the loop 1 which will be presently seized by the beak 160 of the shuttle 155 while the same rotates in the direction of the arrow 162. On slight recession of the needle 49 from its next lowermost position 49'', indicated in broken lines in Fig. 10, the next loop 1' is cast. During the time interval between the casting of the loops 1 and 1', the shuttle 155 has been rotated through two revolutions plus an additional rotation through an angular distance corresponding to the acute angle between the shuttle beaks 160 in the positions shown in Figs. 7 and 10, so that said beak 160 will seize the loop 1' immediately on formation of the same. The additional rotary motion of the shuttle 155 is caused on axial movement of the gear 122 in a certain direction relative to the gear 121. Following this, the needle 49 will be swung back into the axial disposition shown in Fig. 7 and moved into the lowermost position 49', ready to cast the next loop 1 on slight recession from said lowermost position. During the time interval while the needle 49 recedes from the position shown in Fig. 10, swings into the axial disposition shown in Fig. 7, moves into the lowermost position 49' and slightly recedes from said lowermost position into the full line position, shown in Fig. 7, the shuttle 155 has been rotated through two revolutions minus an angular distance corresponding to the acute angle between the shuttle beaks 160 in the positions shown in Figs. 10 and 7. This deductible slight rotation of the shuttle is caused by the axial movement of the gear 122 in the opposite direction relative to the gear 121. Consequently, the shuttle beak 160 is again in a position to seize the loop 1 immediately after the latter is cast. It will now be understood that the shuttle 155 alternately assumes the momentary positions shown in Figs. 7 and 10, i. e., positions in which its beak 160 will presently enter the loops 1 and 1' that are alternately cast by the vibrating needle 49.

The distance between consecutive lock stitches, as formed by the vibrating needle 49 and cooperating shuttle 155, may be varied by loosening the nut 69b on the bolt 69, swinging the link 68 about its pivot 67 into another position, and retightening the nut 69b (Fig. 2) to thereby vary the amplitude of vibration of the needle 49 in a plane at right angles to the needle crank shaft 42. Corresponding adjustment of the bolt 144 on the link 143 in the arcuate groove 145 of the lever 146 will result in such a variation of the two alternating speeds of the gear 121 that the beak 160 of the shuttle 155 will be in loop-seizing position every time the needle 49 casts the alternate loops 1 and 1'.

A bobbin 163, holding a supply of under thread, is rotatable in a bobbin case 164 which is located in an annular recess 167 of the shuttle 155 (Fig. 11) and rotatably supported therein with its hub

165 on a pin 166, projecting from said shuttle. In order to retain the bobbin case in the shuttle and to prevent rotation of the same regardless of the rotary and axial motions of said shuttle, the following structure is provided. As best shown in Fig. 1, the bracket 95 rotatably supports a rod 170 to which the hub 172 of a bobbin retainer 173 is keyed as at 171. The retainer 173 is in form of a fork (Figs. 2 and 7 to 10, inclusive) and preferably welded or otherwise secured to the hub 172. A spring 174 is suitably anchored at 175 to the retainer 173 and snapped into an annular groove 176 in the rod 170, thereby maintaining said retainer in keyed engagement with said rod. Manual removal of the retainer 173 from the rod 170 to permit reloading of the bobbin case is greatly facilitated in that the spring 174 needs to be merely snapped out of the annular groove 176 prior to removal of said retainer.

The bobbin case 164 is provided with an arcuate groove 177 which is concentric with respect to the axis of the rod 170 and receives depending fingers 178 (Fig. 1) of the retainer 173. More particularly, these depending fingers 178 are so angularly spaced that at least one of them projects into the groove 177 at any time when the retainer 173 is rocked by the rod 170. Secured in any suitable manner to the rod 170 is an arm 179, having a forked end 180 into which projects a crank pin 181, adjustably mounted in a diametrical groove 182 of a disk 183. The disk 183 is carried by a stub shaft 184 (Fig. 1) which is rotatably, but axially immovably, mounted in the bracket 127. Also mounted on the stub shaft 184 is a gear 185 which is in constant mesh with a gear 186 on the counter shaft 124. The ratio between these gears is 1 to 1. Hence, during each revolution of the counter shaft 124, i. e., during approximately each revolution of the shuttle, the retainer 173 is oscillated once so that its fingers 178 move alternately out of the arcuate groove 177 in the bobbin case 164 in order to clear the non-twisted loop 1 or 1' which passes completely around the shuttle during approximately each second revolution of the latter. Figs. 8 and 9 illustrate the two angular positions of the retainer 173 in which either of the fingers 178 is momentarily withdrawn from the arcuate groove 177 to provide gaps 187 and 188, respectively, between the shuttle 155 and the fingers 178, through which the loop passes on its travel around the shuttle. The diametrical groove 182 in the disk 183 may be dispensed with and the crank pin 181 may be made integral with said disk 183, in which case the eccentric throw of the pin 181 is so selected that the gaps 187 and 188 are sufficiently wide so as not to obstruct the free passage of a loop around the shuttle regardless of any variation of the amplitude of vibration of the needle and a corresponding variation of the alternating speeds of the shuttle.

As earlier explained, the needle bar 35 has a second oscillatory motion in a plane parallel to the axis of the needle crank shaft 42 and about the pivot 36 of the sleeve 34 as a fulcrum (Fig. 1). The cam groove 55 (Fig. 4), which causes this second oscillating motion of the needle bar 35, is so designed that the needle 49 retracts from the foremost position shown in Fig. 1 in a step-by-step motion for the purpose of producing the zigzag stitches 190 (Fig. 3) which cover the customary underlying stitches (not shown) of a tack. These underlying stitches of the tack may be produced by any conventional mechanism, which is not disclosed as the same does not form

any part of the present invention. The step-by-step retraction of the needle 49 is participated in by the shaft 110 and the thereby carried combined support and drive 97 of the shuttle, so that the latter may cooperate with the needle 49 during its step-by-step retraction. The gear 121 does not participate in the step-by-step retraction of the shaft 110, it being held axially immovable between the bracket 127 and the member 130. However, the rod 170 and the thereby carried bobbin retainer 173 and forked member 179 are moved together with the shaft 110 and shuttle 155 by means of spacers 191 (Fig. 1) which straddle said forked member 179 and are carried by a rod 192, suitably secured to the cam block 96 of the combined support and drive 97. Hence, the retainer 173 remains in permanent cooperation with the bobbin case 164 in the shuttle 155 regardless of the position of the latter during its step-by-step retraction. The crank pin 181 and the disk 183 are axially immovable, but the former is of such length as to remain in registry with the forked end 180 of the member 179 in spite of the movement of the latter to and from disk 183.

Also movable with the combined support and drive 97 on its step-by-step retraction is a throat plate 195 (Figs. 1 and 6) which is secured at 196 to the cam block 96 and has an elongated opening 197 through which the vibrating needle passes on each descent. The throat plate 195 is guided for linear movement in a longitudinal slot 198 in the work table 32, thereby also preventing rotation of the combined support and drive 97 in the bracket 95. The work W lies on the work table 32 and is pressed thereagainst by any conventional presser foot 199 so that the work W will not move with the throat plate 195. The presser foot 199 is preferably normally spring-urged toward the work table 32 and may be lifted in any conventional manner as, for instance, by a foot pedal (not shown).

Provisions are preferably made for varying the length v of the tack (Fig. 3). To this end, the modified construction in Fig. 4a shows that the lever 78 (Fig. 4) has been dispensed with and the lever 79 is pivotally connected at 200 with one end of a link 201 which has its other end adjustably secured within the confines of an arcuate groove 202 of a lever 203 by means of a fork 7 which is preferably manipulated from the outside of the machine and suitably secured in any adjusted position. The lever 203, which is rotatably mounted on a suitably supported pivot 204, has an extending arm 205, carrying a follower 206 which projects into a cam groove 55' in the disk 53a. For sewing a tack, the cam groove 55' has to be of the same or similar shape as the cam groove 55 in Fig. 4, and not of the shape shown in Fig. 4a. The arcuate groove 202 in the lever 203 is concentric with respect to the pivot 200 when said lever assumes the home position shown in Fig. 4a. Consequently, on adjusting the link 201 within the confines of the arcuate groove 202, the extent of said second oscillatory motion of the needle 49 may be varied, resulting in a different length of the tack. Link 201 may be so adjusted that its connection with the arcuate groove 202 is in coaxial alinement with the pivot 204, with the result that no motion is transmitted through the link 201 to the lever 79 in spite of oscillation of the lever 203.

While the preceding description had to do with the formation of lock stitches, the following description has to do with the formation of chain

stitches in the same machine. It is thereby of particular advantage that the combined support and drive 97 may be used interchangeably either with a shuttle 155 such as shown in Fig. 11, or with a rotary looper 207 such as shown in Fig. 15. This rotary looper 207, which is of open-ring shape, has apertures 208 in its periphery which are adapted to receive the pawls 99 of the combined support and drive 97 (Figs. 12 and 14) in such alternate fashion that the looper is at all times in supporting and driving engagement with the pawls 99, yet is allowed to pass completely through a loop without any interference from said pawls. More particularly, the pawls 99 are retracted from the looper as they approach and pass the loop. As best shown in Fig. 15, the looper 207 has its leading end 209 terminate in a loop-seizing beak 210, and has its trailing end 211 formed like a fork, the one leg 212 of which projects considerably beyond the front face 213 of the looper so that the space between the fork legs may be entered by the needle 49. The loop, which is cast by the needle 49 on slight recession from any of its lowermost positions, is seized by the beak 210 of the looper which thereupon passes completely through said loop. Before the looper leaves the loop, the latter has to pass around the forked looper end 211, whereby the loop is widened to such an extent as to form, with the aid of a loop deflector 225 to be described hereafter, the thread triangle 214 shown in Fig. 16 through which the needle passes so as to form a chain stitch in a manner well known to those skilled in the art.

While the shuttle 155 makes approximately two revolutions to one reciprocation of the needle 49, the looper 207 makes approximately one revolution to each reciprocation of the needle. Consequently, in using the machine shown in Fig. 1 for the formation of chain stitches, the ratio between the gears 44 and 128 in the rear of the machine must be 1 to 1. Any suitable provisions may be made for replacing the gears 44 and 128 with new gears of a 1 to 1 ratio and for remeshing the idler gear 129 with said new gears. By way of example, the idler gear 129 may be rotatably mounted on a tubular member 215 (Fig. 1) which telescopes with a cylindrical portion 216 of an arm 217 which is rotatably mounted on a bushing 218 in the machine frame 30. On removing the screw 219, which extends through a lug 220 of the tubular member 215, from the tapped hole 221 in a machined surface 222 of the machine frame 30, the idler gear 129 may be swung from mating engagement with the gears 44 and 128 and the latter may then be replaced by preassigned gears of a 1 to 1 ratio. The idler gear 129 is then moved into mating engagement with the replaced gears and held in mating engagement therewith until the screw 219 is secured in another tapped hole 223 in the machined surface 222 of the machine frame 30.

In Fig. 16, a loop 1' is shown in typical chain-stitch concatenation with the loop 1² which forms the thread triangle 214. The needle 49 is presently passing through the thread triangle 214 and between the legs of the forked looper end 211. The loop deflector 225 is holding the forward side 226 of the loop 1² in such position that the needle 49 may pass therethrough. During the slight further rotation of the looper 207 from the position shown in Fig. 16 into that shown in Fig. 17, the loop 1² has been cleared by the trailing end 211 of the looper and will be presently withdrawn from the loop deflector 225

and taken up by the take-up device 158 (Fig. 1). Also, the needle 49 has descended to its one lowermost position 49' shown in broken lines in Fig. 17, and then receded into the full line position shown in this figure, thereby casting the loop 1³ which will be presently seized by the beak 210 of the looper. While the looper passes through the loop 1³, the deflector 225 is shifted to the right as viewed in Figs. 18 and 19 to engage and deflect the forward leg of said loop and form a thread triangle by the time the forked looper end 211 passes through the latter and the needle 49 enters said loop on its descent into its other lowermost position 49'' (Fig. 19). Continued rotation of the looper into the position shown in Fig. 20 will effect the release of the loop 1³ from the looper, whereupon the take-up device 158 comes again into operation to withdraw said loop 1³ from the deflector 225 and up against the work W. The next loop 1⁴ which has just been cast by the needle 49 on slight recession from its lowermost position 49'', is immediately seized by the beak 210 of the looper 207 which then passes therethrough. The deflector 225 now swings in the opposite direction through the position shown in Fig. 21 and into the position shown in Fig. 16, in order to sweep the forward leg of the loop 1⁴ to the left as viewed in Fig. 16 so that said loop may be entered by the needle 49 on its next descent into the lowermost position 49'. In this fashion, a plurality of chain stitches is formed which may be arranged in the zigzag fashion shown in Fig. 3 to form the covering stitches of a tack.

It is evident from the preceding description that the deflector 225 oscillates once during two consecutive revolutions of the looper. Inasmuch as the loop deflector 225 may be interchangeable with the bobbin-case retainer 173 on the rod 170 (Fig. 1), and as said retainer 173 oscillates once during each revolution of the shuttle 155, the gear ratio between the gears 185, 186 (Fig. 1) must be variable from 1 to 1 to 2 to 1 in order to properly time the operation of the loop deflector 225. This is accomplished by replacing the gears 185, 186 with new gears 230 and 231 (Figs. 12 to 14 inclusive) which have a ratio of 2 to 1.

While it is not imperative to make the crank pin 181 radially adjustable on the disk 183 as shown in Figs. 12, 16 and 19, because a slight variation of the amplitude of oscillation of the needle 49 and a corresponding variation of the alternate rotary speeds of the looper will not ordinarily result in a defective timing of the loop deflector 225, it is nevertheless preferable to make this crank pin 181 adjustable for operating either the bobbin retainer 173 or the loop deflector 225 either one of which may be placed on the rod 170 (Fig. 1) for the formation of lock stitches or chain stitches, respectively.

The described mechanism, which may produce either lock stitches or chain stitches, is also particularly adapted for sewing on buttons having one or more groups or series of holes through which the stitches are to be laid. If a button with only two holes is to be attached, the link 201 in Fig. 4a is so adjusted that its connection with the lever 203 within the confines of the arcuate groove 202 is in coaxial alignment with the pivot 204 so that no longitudinal motion is transmitted to the needle-oscillating bar 63. In this way only the lateral vibration of the needle in a plane at right angles to the needle crank shaft 42 is utilized for laying the stitches through the two holes of the button. However,

if the button has more than two holes, i. e., more than one group or series of holes, the needle 44 will have to move laterally in the two transverse directions of which it is capable. However, no step-by-step retracting motion of the needle and of its cooperating thread handling element underneath the work table 32, as caused by the shape of the cam groove 55 in Fig. 4, can be utilized because the stitches through each group of holes must be superposed and cannot progress in a zigzag fashion. Recourse is, therefore, had to the cam disk 53a (Fig. 4a) with its cam groove 55', instead of the cam disk 53 (Fig. 4) with its cam groove 55. This groove 55' is designed for the attachment of a button having two pairs of holes as follows from the two diametrically opposite cam portions 235 which are joined by concentric groove portions 237 and 238. While the follower 206 of the lever 203 travels in either of the concentric groove portions 237 or 238, the needle is vibrated in a plane at right angles to the needle crank-shaft 42 and forms a group of superposed stitches through the first group of holes.

On the first cooperation of the follower 206 with a groove portion 235 during the sewing operation, the needle 49 and the cooperating thread-handling element underneath the work table 32 are shifted from operative alignment with the first pair of holes of the button into operative alignment with the other pair of holes thereof. The stitches laid through both pairs of holes of the button may either be lock stitches or chain stitches, depending on the use of a shuttle or of a looper. By making appropriate adjustments of the lateral motions of the needle and corresponding adjustments of the alternate speeds of the thread-handling element, the present machine can be used for attaching buttons having differently spaced holes.

While lock stitches do not necessarily require a tying stitch at the end of a sewing operation, chain stitches should terminate in at least one tying stitch. Hence, regardless of the use to which the present machine may be put, provisions are preferably made in the machine for making a tying stitch at the end of a sewing operation. The present invention is, however, not concerned with the formation of a tying stitch, wherefore neither disclosure is made, nor a description given, of structure for forming a tying stitch. Any conventional structure may be added to the machine, if desired, for forming one or more tying stitches at the end of a sewing operation.

While it was stated that the present machine can be readily used for sewing on buttons, no effort is made to disclose certain mechanisms customarily used in button sewing machines. It is deemed unnecessary to show, for instance, a button clamp or a thread severing device, etc.

I claim:

1. In a sewing machine, the combination of a reciprocating and laterally movable needle; a laterally immovable thread-handling element rotatable about an axis transverse to the direction of lateral movement of the needle; and two permanently meshing helical gears rotatable about parallel axes, the driven gear thereof being drivingly connected with said element and one of said gears being axially movable relative to the other gear.

2. In a sewing machine, the combination of a reciprocating needle movable laterally in several directions; a laterally immovable thread-handling element having a loop-seizing beak and being

5 axially movable with the needle in one of said lateral directions; means for rotating said element in one direction; and means associated with said rotating means for varying the rotation of said element to advance or retract the beak thereof angularly with respect to its path of rotation to such an extent that the leading point of said beak always passes the reciprocating needle at the same distance from the needle point in any lateral position of said needle.

10 3. The combination in a sewing machine as set forth in claim 2, in which said rotating means includes two permanently meshing helical gears rotatable about parallel axes, the driven gear thereof being drivingly connected with said element, and said associated means includes a device for moving one of said gears axially relative to the other gear.

15 4. In a sewing machine, the combination of a reciprocating and laterally vibratory needle; a laterally immovable thread-handling element rotatable about an axis transverse to the plane of vibration of the needle; means for rotating said element in synchronism with each needle cycle, said means including two permanently meshing helical gears rotatable about parallel axes and one of said gears being axially movable relative to the other gear; a first adjustable device for imparting vibrations of variable amplitude to the needle; and another adjustable device for axially reciprocating said one gear in timed relation with the needle reciprocation and through such a distance that said element remains in synchronism with the vibrating needle.

20 5. The combination in a sewing machine as set forth in claim 4, in which said other device includes a pivoted shifter lever for said one gear, a rotary cam, a pivoted follower therefor having an arcuate groove, and a link having one end pivotally connected with said shifter lever and its other end adjustably pivoted in said groove which is concentric about the pivot connection between said link and shifter lever when the needle is in the middle position of its vibration.

25 6. The combination in a sewing machine as set forth in claim 4, in which said first device is adjustable for imparting to the needle vibrations of an amplitude variable between zero and a pre-assigned maximum, and said other device is adjustable for reciprocating said one gear through a distance variable between zero and a pre-assigned maximum distance.

30 7. The combination in a sewing machine as set forth in claim 4, in which said first device is adjustable for imparting to the needle vibrations of an amplitude variable between zero and a pre-assigned maximum, and said other device includes a pivoted shifter lever for said one gear, a rotary cam, a pivoted follower therefor having an arcuate groove, and a link having one end pivotally connected with said shifter lever and its other end adjustably pivoted in said groove which extends through the pivot axis of said follower and is concentric about the pivot connection between said link and shifter lever when the needle is in the middle position of its vibration range.

35 8. In a sewing machine, the combination of a reciprocating needle laterally vibrating in one direction and laterally movable in a direction transverse to said one direction; a first rotary shaft axially movable in said transverse direction; a thread-handling element carried by said shaft; means for simultaneously moving said needle and shaft equal amounts in said trans-

verse direction; another shaft parallel to said first shaft and driven in timed relation with the needle reciprocation; two permanently meshing helical gears mounted on said shafts, respectively, for rotation therewith, one of said gears being axially movable relative to the other gear; and mechanism for axially reciprocating said one gear in timed relation with the needle vibration and through such a distance that said element is rotated in synchronism with each working cycle of the vibrating needle.

9. In a sewing machine, the combination of a reciprocating needle having a lateral vibration of variable amplitude; a laterally immovable shuttle; adjustable means rotating said shuttle at alternately different speeds so as to maintain its rotation in constant synchronism with the needle reciprocation during vibration of any amplitude; a bobbin case freely rotatable in said shuttle and having a circular groove in its exposed front wall; a bobbin case-retaining member pivoted on an axis concentric to said groove and having two fingers so angularly spaced that at least one is in registry with said groove at all times; and adjustable means rocking said member through a variable angular range so that each finger leaves said groove to provide a gap therebetween through which the passing leg of the needle

thread loop travels regardless of the variable alternate rotary speeds of the shuttle.

10. In a sewing machine, the combination of a reciprocating needle movable laterally in one direction; a looper; a combined support and drive for said looper movable axially of the latter in said one direction; a loop deflector; a shaft carrying said deflector and axially moving together with the combined support and drive in said one direction; and means for oscillating said shaft in timed relation with said drive so that the loop deflector may cooperate with the looper in any position of the latter.

11. In a sewing machine, the combination of a reciprocating needle movable laterally in one direction; a shuttle; a removable bobbin case in said shuttle; a combined support and drive for the shuttle movable axially of the latter in said one direction; a shaft oscillatable about its own axis and axially moving together with said combined support and drive in said one direction; a retainer carried by said shaft; and means for oscillating said shaft in timed relation with said drive whereby said retainer cooperates with the bobbin case to retain the same in the shuttle in any axial position of the latter and permit the complete passage of the thread of a loop on the shuttle between said retainer and bobbin case.

SAMUEL W. AVIS.
